CLAIM

The ornamental design for an electronic data recorder as shown and described.

DESCRIPTION

FIG. 1 is a front elevational view of an electronic data recorder showing the first embodiment of my new design; FIG. 2 is a rear elevational view thereof; FIG. 3 is a left side view thereof; FIG. 4 is a right side view thereof; FIG. 5 is a top plan view thereof; FIG. 6 is a bottom plan view thereof; FIG. 7 is a perspective view thereof; FIG. 8 is another perspective view thereof, shown in a state for use with the kickstand extended; FIG. 9 is a front elevational view of an electronic data recorder showing the second embodiment of my new design; FIG. 10 is a rear elevational view thereof; FIG. 11 is a left side view thereof; FIG. 12 is a right side view thereof; FIG. 13 is a top plan view thereof; FIG. 14 is a bottom plan view thereof; FIG. 15 is a perspective view thereof, shown in a state for use with the kickstand extended; and, FIG. 16 is another perspective view thereof.

The broken lines shown in the drawings depict portions of the electronic data recorder that form no part of the claimed design.

1 Claim, 14 Drawing Sheets
